Attorney-

UNITED STATES PATENT OFFICE.

SAMUEL B. THOMSON, OF PATERSON, NEW JERSEY.

CLOTH BOARD OR REEL.

1,199,319.

Specification of Letters Patent. Patented Sept. 26, 1916.

Application filed July 12, 1915. Serial No. 39,508.

To all whom it may concern:

Be it known that I, SAMUEL B. THOMSON, a citizen of the United States, residing at Paterson, in the county of Passaic and State 5 of New Jersey, have invented certain new and useful Improvements in Cloth Boards or Reels, of which the following is a specification, reference being had therein to the accompanying drawing.

10 The objects of my invention are to provide a cloth-board or reel for woven silk or other fabrics, formed from an integral sheet of material so folded as to form adjacent internal receptacles or boxes which are 15 inclosed within by the enveloping flaps of the blank, the walls of the interior boxes to reinforce and strengthen the reel, and to so construct a cloth-board or reel which will be 20 simple in construction, strong, light and durable.

The invention consists of a rectangular reel having a plurality of internal adjacent boxes all formed from an integral blank, the flaps of which envelop the internal boxes 25 and caps, one fitting over each end of the reel as shown in the accompanying drawings.

In the drawings, Figure 1 is an illustration in perspective of my completed cloth- 30 board or reel. Fig. 2 shows the blank in perspective partially folded and illustrates the method of folding the same; Fig. 3 shows plan view of the blank cut and prepared for folding, as indicated by dotted 35 lines; Fig. 4 is a sectional view on the line 4—4 of Fig. 1 illustrating the reinforcing walls of the internal boxes; Fig. 5 is a sectional view on the line 5—5 of Fig. 1; Fig. 6 is a perspective view of a portion of a reel, 40 the end of which is not provided with the cap C, shown in Fig. 1; Fig. 7 is a perspective view of a reel showing fabric wound thereon, portion of the reel and fabric being 45 broken away leaving part of the reel projecting beyond the fabric.

Similar letters refer to similar parts throughout the several views.

The most noticeable feature of my cloth-board is the absence of wood or metal in the 50 construction thereof.

The cloth-board is made substantially rectangular in shape, the ends being flat and the longitudinal edges being semi-circular in form. These cloth-boards are sometimes 55 called bolt-boards and various other names, and are used by manufacturers as receptacles

upon which is wound or rolled the woven cloth or fabric, the edges of the fabric usually being flush with the flat end of the reel, as is shown in Fig. 7 of the drawings, 60 which represents a portion of a cloth-board or reel with fabric wound thereon, a portion of the reel being broken away and also a portion of the silk fabric permitting the broken end of the reel to project from the 65 broken off portion of the silk fabric, which illustrates the method of winding the woven goods upon the reel or cloth-board, the central portion represented by dotted lines being the reel R and the outer portion being 70 the woven silk fabric S.

Fig. 1 shows my completed cloth-board or reel which is constructed from the blank B, shown in Fig. 3. Said blank is cut out as shown in Fig. 3 and the flaps —a— are bent 75 over on the outer lines shown in said figure, to form boxes B', B'', B³, and B⁴, which four boxes are in turn folded over, as shown in Fig. 2, making the double compartments B⁵ and B⁶ adjoining each other in the middle 80 portion of the blank B, a'—a' forming the outer ends of B⁵ and B⁶, and the side flaps A and D are then turned over the double compartments B⁵ and B⁶ and a cap C of similar or other suitable material is secured 85 over each end of the reel thus formed, as shown in Fig. 1. The sides and ends —a— and a' of the internal boxes act as braces, reinforcing and strengthening the cloth-board or reel and giving it the necessary 90 rigidity for properly holding the fabric wound upon the reel.

It is obvious that my reel so constructed from paper board, vegetable fiber board or other suitable substance, is so braced longitudinally and transversely, by the tiers of internal adjacent compartments or boxes, as to obviate the necessity and to avoid the objections of or to a wooden or metal frame. As shown in the drawings there are tiers of 100 parallel, internal adjacent boxes, or internal boxes placed one above the other, some transversely and some longitudinally of the reel. The parallel compartments, B' and B'', folded together form the compartment 105 B⁵, the parallel compartments B³ and B⁴ folded together form the compartment B⁶. The compartments B⁵ and B⁶ folded over on the blank B, form two parallel, adjacent interior compartments inclosed by the overlapping flaps A and D of the blank B, thus 110 reinforcing or strengthening the reel, R, both

longitudinally and transversely. There are thus tiers of internal compartments, or compartments one above the other, in both directions. The result is a reel or cloth-board 5 having all the requisites and advantages of simplicity, durability, lightness, strength and inexpensiveness.

It is also obvious that such a cloth-board or reel is not apt to split, check or warp, and 10 may be produced of vegetable fiber board of any desired strength and thickness. The tiers of internal adjacent compartments or boxes may be permanently united to the enveloping or outer flaps by any suitable adhesive substance or not, without departing 15 from the scope of the invention.

Caps C may be secured permanently to the 20 ends of the reels or not. Said caps may be made to fit sufficiently snug as to efficiently hold the folded portions of the blank in proper position for use, without the employment of any adhesive substance.

In the relative arrangement of the tiers of 25 parallel boxes one upon the other, both transversely and longitudinally, I secure and provide a reel of great utility and durability, the purpose thereof being to give strength, rigidity, lightness and long life to the reel by preventing the collapse of the reel so that 30 the reel will retain its shape and be adapted to hold the fabric so that it will lie flat and smooth on the reel.

It is not intended to limit the invention to 35 empty internal compartments or boxes for the purpose of reinforcing and strengthening longitudinally and transversely a reel or cloth-board composed of an integral blank, folded as shown and described, as said compartments may be utilized for the purpose

of carrying a non-metallic or other substance 40 for reinforcing or other purposes.

I claim:—

1. A cloth-board or reel for the purpose specified, comprising a blank constructed of a single piece of material, including a central rectangular portion, end portions provided with foldable flaps to form a plurality of compartments adapted to be folded over on and to occupy adjacently the central longitudinal portion of the first mentioned central rectangular portion and adapted to be enveloped and inclosed by the foldable sides of said central rectangular portion.

2. A cloth-board or reel for the purpose specified, comprising a blank constructed of a single piece of material, including a central rectangular portion, end portions provided with foldable flaps to form a plurality of compartments adapted to be folded over on and to occupy adjacently the central longitudinal portion of the first mentioned central rectangular portion and adapted to be enveloped and inclosed by the foldable sides of said central rectangular portion, in combination with caps adapted to fit snugly over the ends of the reel so constructed.

3. A reel comprising tiers of adjacent internal compartments provided with an enveloping wrap, the whole formed from an integral blank, in combination with caps adapted to fit snugly over the ends of the reel so constructed.

In testimony whereof I affix my signature in presence of two witnesses.

SAMUEL B. THOMSON.
